(57) **CLAIM**

The ornamental design for a machining center, as shown and described.

DESCRIPTION

FIG. 1 is a perspective view 1 of a machining center showing my new design;

FIG. 2 is a perspective view 2 thereof;

FIG. 3 is a front elevation view thereof;

FIG. 4 is a back elevation view thereof;

FIG. 5 is a top plan view thereof;

FIG. 6 is a bottom plan view thereof;

FIG. 7 is a right side elevation view thereof;

FIG. 8 is a left side elevation view thereof; and,

FIG. 9 is a perspective view of an open state thereof.

The claimed machining center has a door formed in the cover surrounding the work storage section, and the door can be opened to allow direct access to the work storage section. The broken lines in the drawings depict portions of the machining center which form no part the claimed design.
